(57) **CLAIM**

The ornamental design for a laundering device, as shown and described.

DESCRIPTION

FIG. 1 is a perspective view of a laundering device showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dashed line in FIGS. 1, 2 and 3 represents stitching which is a part of the claimed design.

The broken line showing indicia in FIGS. 1 and 2 is for illustrative purposes only and form no part of the claimed design.
